UNITED STATES PATENT OFFICE.

FRANK R. STEHM, OF DES MOINES, IOWA, ASSIGNOR, BY DIRECT AND MESNE ASSIGNMENTS, TO THE ENAMEL CONCRETE AND MACHINERY COMPANY, OF DES MOINES, IOWA, A CORPORATION OF SOUTH DAKOTA.

METHOD OF MAKING ARTIFICIAL STONE.

1,182,862.

Specification of Letters Patent.

Patented May 9, 1916.

Application filed May 14, 1908. Serial No. 316,892.

To all whom it may concern:

Be it known that I, FRANK R. STEHM, a citizen of the United States, residing at Des Moines, in the county of Polk and State of Iowa, have invented a certain new and useful Method of Making Artificial Stone, of which the following is a specification.

My object is to provide an improved method of producing artificial stone having a smooth and glossy surface that will render the finished stone non-absorbent and further to provide a method by which finished artificial stone of this kind may be produced cheaply and without the application of heat or use of polishing devices.

My invention consists in the several steps of the process and in their arrangement and combination with each other, whereby the objects contemplated are attained, as hereinafter more fully set forth, pointed out in my claim and illustrated in the accompanying drawings, in which—

Figure 1 shows a perspective view of an apparatus designed for the practice of my improved method. Fig. 2 shows a similar view with the mold elevated above the completed artificial stone. Fig. 3 shows a vertical, longitudinal, sectional view of the finishing plate detached. Fig. 4 shows a perspective view of the same plate. Fig. 5 shows a transverse, sectional view of the finishing plate. Fig. 6 shows a central, longitudinal, sectional view of a mold, a finishing plate and a partition in the mold, said finishing plate having therein a quantity of surfacing material. Fig. 7 shows a similar view with the mold filled with material for forming the body of the stone and illustrating the surfacing material forced upwardly between the partition and the adjacent end of the finishing plate. Fig. 8 shows a similar view with a presser plate introduced into the mold and the material for forming the body of the artificial stone compressed and the finishing material between the partition and the adjacent end of the finishing plate raised to a point above the top of the mold. Fig. 9 shows a similar view with more material for forming the body of the stone added after the removal of the presser plate, and Fig. 10 shows a similar view with the presser plate in position and the artificial stone completely formed and the partition removed.

Referring to the accompanying drawings, 55 the apparatus that I have illustrated for carrying out my improved method is composed of a frame 10 having thereon supports 11 to receive an off-bearing plate 12, which plate is formed with a raised central portion. At the top of the frame 10 is a shaft 13 provided with crank arms 14 and links 15 connected therewith and having at their lower ends the cross pieces 16.

The numeral 17 indicates a mold designed 65 to rest upon the off-bearing plate and to have its ends project beyond the raised central portion thereof, so that said ends may rest upon the cross pieces 16 and so that a partial revolution of the shaft 13 will elevate the mold from the off-bearing plate 12. The finishing plate is formed of thin 70 springing metal and comprises a base 18 having upturned side margins 19 and one upturned end margin 20, an upright end 75 portion 21 at right angles to the base 18 and side margins 22 thereon projected inwardly over the bottom piece 19. At the intersection of the parts 18 and 21 is a slightly curved corner portion 23. This 80 finishing plate is of a size to enter the mold with the outer surface of the upright end 21 flush at one end of the mold and the upturned margin 20 flush at the other end of the mold and the outer surfaces of the margins 19 and 22 flush with the sides of the mold. In order to accomplish the best results and to produce a finished stone having a hard, crystallized, smooth and glossy surface, the inner faces of the finishing 85 plate are provided with a non-erosive, moisture repellent surface that will not adhere to the dried and hardened stone making material. A satisfactory surface of this kind may be obtained by means of a coating 90 of japan applied thereto and baked.

I have provided for pressing material into the mold as follows: 24 indicates a shaft mounted in the frame 10 and provided with a crank arm 25 connected to the presser plate 26 whereby a rocking movement of the said shaft will cause the presser plate to move up and down, said presser plate being designed to enter the mold. A detachable partition 27 is provided, made of thin 100 metal and having a cross piece 28 at its top designed to rest upon the top of the mold with said partition projecting trans-

versely of the mold near the end where the end 21 of the finishing plate is located, the bottom of said partition being spaced apart slightly from the finishing plate, substantially as shown in Fig. 6, the lower end of said partition normally inclined slightly toward the center of the mold.

In practising my improved method, I place a finishing plate in a mold and then 10 place the mold and finishing plate on the off-bearing plate. I then place the partition 27 in position, as shown in Fig. 6. I then prepare a quantity of surface forming material for the stone, composed of cement 15 or its equivalent, containing a quantity of liquid so that it will flow readily. I then pour this cement upon the bottom of the finishing plate, so that it substantially fills the portion of the plate within the upturned 20 margins of the bottom. This stage of the process is shown in Fig. 6. I then prepare a quantity of material to form the body of the stone. This may be composed of cement and sand or their equivalents, well 25 moistened but not in liquid form and I place a quantity of this material in the mold. The weight of this will force the surfacing material upwardly between the partition and the upwardly projecting end 30 of the finishing plate, as shown in Fig. 7. I then introduce a presser plate into the mold and force it downwardly therein to compress the material. This presser plate will, when being forced downwardly into 35 the mold, move the partition to a substantially vertical position, as shown in Fig. 8, and will also cause the surfacing material to flow up to the top of the mold. This stage of the process is illustrated in Fig. 8. I 40 then remove the presser plate and again fill up the mold with more of the same material for forming the body of the stone. I then remove the partition and introduce a presser plate of the size that will fit the 45 interior of the mold and apply pressure to the material sufficient to fill up the opening left by the removal of the partition and to compress the material into a sufficiently compact condition. I then elevate the mold 50 from the off-bearing plate and from the stone and the finishing plate, the presser plate being left resting against the top of the stone in order to permit the upward withdrawal of the mold. I then jointly 55 remove the off-bearing plate and the stone with its finishing plate resting upon the off-bearing plate and remove same from the machine and place them in a convenient position for drying. After the completed 60 stone has dried for a sufficient period, varying from two to four days, under proper conditions, the finishing plate may be removed from the stone by springing the side 21 and bottom 18 straight outwardly from the stone. In this way the finishing plate

need not be drawn across the surface of the stone but is moved straight outwardly so that the surface of the stone is not marred or scratched during this removal movement. If the finishing plate has been provided 70 with a surface that is smooth and that will not adhere to the cement, it will be found that upon its removal, the adjacent surfaces of the stone will have crystallized and formed a surface that is a replica of the surface against which it rested during the crystallizing process and the finished product will have a smooth, glossy surface that will not absorb moisture. 75

By having the finishing plate placed directly upon the off-bearing plate, the mold may be removed by elevating it away from the off-bearing plate without danger of disturbing the positions of the stone and the finishing plate, for obviously, if either the 80 finishing plate or the stone were handled or touched before drying, there would be a great possibility of jarring the finishing plate loose and thus destroying its contact 85 with the adjacent surface of the stone and unless this contact is complete during the entire crystallizing and drying process, the finished surface will not be as smooth and glossy as it otherwise would. 90

By providing a partition adjacent to one 95 end of the mold and spaced apart from the bottom of the mold, the surfacing material in a liquid condition may be made to flow upwardly between the partition and the adjacent end of the mold, by the insertion of 100 a quantity of the material for forming the body of the stone, and by applying pressure on top of this material. It frequently happens that when the surfacing material in liquid form is placed against a finishing plate, a certain quantity of air is retained 105 between the plate and stone, which air forms bubbles and if not expelled would mar the finished surface of the stone. I have found that by applying pressure to the top 110 of the stone that air bubbles may all be expelled and the surface of the stone left perfectly smooth. After the stone has dried adjacent to the finishing plate for a sufficient period of time, the surface nearest 115 the plate will crystallize and then, if the plate is removed by springing the sides and bottom straight outwardly from the stone, this crystallized and glossy surface will not be marred and when the finishing plate is removed, its surface nearest the stone will be perfectly clean and free from material of 120 which the stone is formed. If in handling the stone before drying, the plate should spring away from the stone and permit the entrance of air, the crystallizing process would not take place and produce so perfect a surface as though the drying and crystallization took place with the plate 125 tightly held against the stone. 130

The terms "artificial stone" and "concrete" used in this application are intended to apply to the same thing, and relate to a material formed of particles held together by cementitious substances.

Having thus described my invention, what I claim and desire to secure by Letters Patent of the United States, therefore, is—

The method of molding plastic material which consists in providing a finishing plate having an upturned end portion and an encircling rim, placing said finishing plate in a mold, introducing a partition adjacent the upturned end portion, filling the bottom portion of said plate with a veneer composition

then introducing coarser material to form the body of the molded article, and applying pressure to the top of said coarser material whereby said veneer composition will be forced upwardly between the end portions of the finishing plate and the partition, and thereafter removing the partition and continuing the pressure whereby the veneer and body material become incorporated together.

Des Moines, Iowa, May 5, 1906.
